RONALD FRANCIS McFEELY, OF BEVERLY, MASSACHUSETTS, ASSIGNOR TO UNITED SHOE MACHINERY COMPANY, OF PATERSON, NEW JERSEY, A CORPORATION OF NEW JERSEY.

SHOE-FORMING MACHINE.

1,042,582.

Specification of Letters Patent.

Patented Oct. 29, 1912.

Continuation of application Serial No. 509,684, filed July 20, 1909. This application filed October 16, 1909.
Serial No. 523,072.

To all whom it may concern:

Be it known that I, RONALD F. McFEELY, a citizen of the United States, residing at Beverly, in the county of Essex and State 5 of Massachusetts, have invented certain Improvements in Shoe-Forming Machines, of which the following description, in connection with the accompanying drawings, is a specification, like reference characters on 10 the drawings indicating like parts in the several figures.

This invention relates to shoe forming machines and is shown as embodied in a machine for shaping a lasted shoe to prepare it for the reception of an outer sole. 15

An important feature of this invention consists in the combination of a reciprocating bottom pounder with a side beater which is so arranged relatively to its actuating 20 mechanism that the beater remains at rest until it has been pressed upon by the work to establish an operative connection with its actuator.

The beater is preferably so mounted that 25 when it is actuated it moves upwardly, as well as outwardly toward the shoe, so that it tends to work the stock toward the edge of the shoe bottom. The side beater is arranged to serve as the side rest for the 30 shoe and assist the operator in presenting the shoe in proper relation to the bottom pounder. The side beater may serve the purpose of a guiding device alone when a portion of the shoe is being treated which 35 does not require beating at the side and then, as the operation progresses, and the portion of the shoe is reached which it is desirable to beat on the side, the operative connection of the beater to its actuator may 40 be established by increasing the pressure of the shoe against the beater. It is characteristic of this beater that it remains continuously in engagement with the upper and beats the shoe by repeated outward and up- 45 ward impulses as distinguished from blows imparted by moving the beater away from the side of the shoe and then against it as has heretofore been proposed.

A further feature of this invention con-

sists in providing means for automatically 50 moving and holding the shoe laterally toward and in operative relation to the devices for working upon the shoe. More particularly and as herein shown this feature consists in providing means for maintaining 55 the shoe against the side beaters above referred to, whether or not the side beaters are associated with a bottom beater, with sufficient pressure to render the side beaters operative without effort on the part of the 60 workman.

It is found to be a great relief to the workman and to insure more uniform and better results to cause the machine to hold the shoe in position to receive the action 65 of the beaters of which the one shown as operating on the bottom of the shoe as well as the side beaters constantly act to force the shoe laterally away from the machine. This novel feature is embodied in means 70 which operates to press the shoe yieldingly against the side beaters while permitting the shoe to be turned and fed along, which is the only work required of the workman, in accordance with this feature of the in- 75 vention, while the beating operation on a shoe is in progress. The shoe holding means is arranged to permit movement of the shoe and its carrier away from the machine to facilitate the application and removal of 80 the shoe and to lock the shoe carrier automatically in its position remote from the machine. The shoe carrier is shown as a heel spindle adapted to hold welt shoes for the operation of beating the heel seats, but 85 the invention is as well applicable to use with a shoe carrier for supporting a shoe for the entire bottom to be beaten such, for example, as the jack shown in my co-pending application Ser. No. 509,684, filed July 20, 1909, of which the present application 90 is a continuation as to subject matter which is common to it and to the disclosure in that application. It will be understood from the foregoing that in this embodiment of 95 the invention the heel spindle is a carrier that is movable, either by operating means connected with it or by force transmitted

through the shoe, to present the shoe to the side beaters, and that such presentation of the shoe in this machine can be made to establish an operative connection between 5 normally stationary side beaters and their actuator; and furthermore, that the machine preferably includes means acting through the shoe carrier and tending normally to press the carrier and the shoe toward the 10 machine, and also means to lock the carrier and the shoe in a position away from the machine.

These and other features of the invention will be more fully explained in connection 15 with the description of the machine in which they are herein shown and embodied and will then be pointed out in the claims.

Figure 1 is a side elevation of the machine which is of the same general type as 20 that shown in my earlier application; Fig. 2 is a plan view on line 2—2, Fig. 1; Fig. 3 is a perspective view for the purpose of illustrating the side beater.

The column 2 of the machine has a head 4 25 provided with bearings in which is mounted a shaft 5 which drives, by means of an eccentric stud 3, a V-shaped rocker 6. In the front face of the rocker is formed a groove 7 by which is made a sliding connection with 30 a link 8, having formed upon it, or upon a block connected with it, a segment rack by means of which the link can be moved upwardly or downwardly toward and from the center of oscillation of the rocker. The 35 rack is engaged for this purpose by a pinion 12 meshing with a segment lever 14 connected by rod 11 with a foot treadle which, as in the machine of the prior application, is also a starting treadle connected with a 40 rocking lever 18, Fig. 3, and is arranged to be first depressed for throwing in a clutch 17 that drives the shaft 5, and then to be further depressed for adjusting the link relatively to the rocker to vary the length of 45 the stroke imparted to the link.

The initial depression of the starting treadle to throw in the clutch 17 for driving the shaft 5 at the same time operates through the segment lever 14 to turn the 50 pinion 12 to move the segment rack and link 8 upwardly from the lowermost position of the link toward the center of oscillation of the rocker 6. This lowermost position of the link 8 is preferably at an approximately 55 neutral point with respect to the axis of oscillation of the rocker so that in this position the link 8 has little or no movement imparted to it. Preferably, too, the arrangement is such that, upon depression of the 60 treadle, the link 8 will not be moved from its neutral position until after the clutch 17 is thrown in and the shaft 5 is thus started. Thereafter, a slight further depression of

the treadle will move the link 8 upwardly a sufficient distance to cause short strokes to 65 be imparted to the said link while, upon still further depression of the treadle, the strokes imparted to the link 8 may be lengthened as desired without affecting the clutch and hence without discontinuing the 70 operation of shaft 5.

The link 8 is joined at its front end to a vibrator 15 for the tool carrier 16 in which is mounted the bottom pounding tool 20. The vibrator and the carrier are both 75 mounted on the same pivot or fulcrum 18 and the upper arm of the vibrator extends into an inclosed space in the tool carrier where it is located between two cushions 19, which preferably will be rubber blocks. The 80 arrangement of these cushions within an enclosure in the tool carrier is an improvement over my prior construction in that it protects the rubber blocks from the oil and dust which would otherwise deteriorate the rubber. The bottom pounding tool will be actuated from and toward the shoe by the described connection 16, 15, 8, 6 with the eccentric 3, and the tool is preferably mounted to slide lengthwise in its carrier 16. With 90 this arrangement the tool is actuated backwardly in its carrier by its inertia as the carrier completes its upstroke and is actuated forwardly by its inertia and a spring 21 to force the upper inwardly from the 95 edge of the shoe when it comes down upon the shoe, all as more fully explained in said prior application.

The shaft 5 is provided with a cam 25 adapted to operate a vibrator 26 which is 100 fulcrumed in the machine at 28 and connected to a tool carrier 30 on which the side beating tools are mounted. A spring 32 normally holds the vibrator and the tool carrier forwardly with relation to the fulcrum 28 and maintains the vibrator out of contact with the cam 25. The tool carrier 30 is at its forward end forked to extend under the bottom pounder and has laterally projecting ledges 34 arranged between a 110 supporting member 35 on the head 4 and a plate 36 at the lower end of a spring pressed plunger 38. The ledges 34 are inclined as appears clearly in Fig. 1, so that as the tool carrier is moved forwardly, the side beaters 115 are given a component of upward movement which causes them to work the upper toward the edge of the last. The side beating tools 40, of which one is arranged on each side of the bottom pounder 20, are swiveled 120 upon the tool carrier 30 to turn about horizontal and upright axes, as shown, to enable them to adapt themselves to the contour of the shoe. The tool carrier has stop faces at 42 which limit the tipping movement of the 125 side beaters about their horizontal axes and

the beaters are formed with downwardly and backwardly receding faces.

It will be apparent from the above description, that the bottom pounding tool 20 5 may be started or stopped entirely independently of the side beating tools 41 and while the latter continue in operation merely by so positioning the treadle that the link 8 is in its neutral position without, 10 however, throwing out the clutch 17. Similarly, so long as the clutch 17 is not affected and the shaft 5 continues to revolve, the side beaters 40 may be started or stopped at will independently of the bottom pounder 20 15 and while that tool continues in operation.

The shoe carrier herein shown comprises a heel spindle 50 pivotally supported at its lower end by a horizontally adjustable bar 52. The spindle is preferably vertically 20 unyielding but readily adjustable lengthwise as explained in my prior application. The spindle is guided in a yoke member 55 which extends laterally from the frame of the machine and also within a slide 56 which 25 is movable horizontally in guideways in the yoke 55 and is pressed normally toward the frame of the machine by springs 58. This slide is provided at the outer side of the spindle with a spindle engaging block 60 30 turning on a horizontal axis and at the inner side with a latch 62 pivoted at 63. The latch has a horizontal arm the end face of which is adapted to engage with an end face 65 on the yoke when the spindle and 35 slide are moved away from the machine into position for the removal or application of a shoe and to lock the spindle in this shoe receiving position. A spring 66 actuates this horizontal arm into position to engage 40 the abutment when the spindle is so moved outwardly. An upwardly extending arm of the latch stands in position to be engaged by the spindle when the latch is locked and to be rocked into position to turn the 45 horizontal arm away from the abutment so that merely by pressing the shoe and spindle toward the machine the latch is unlocked and the springs 58 are permitted to draw the shoe into operative relation to the tools. 50 Upon such movement of the spindle with the shoe toward the beating tools, the shoe is not only positioned for the action of the bottom beating means, but, at the same time, by such movement of the spindle and shoe, 55 the vibrator 26 is brought into contact with the cam 25 and the operation of the side beating means is started. When it is desired to move the shoe away from the machine that is done against the resistance of 60 the springs 58 and the latch is automatically actuated by the spring 66 to lock the spindle in the remote position. Upon such reverse movement of the spindle and shoe

away from the machine the operative connection between the vibrator and its cam 65 is broken and the operation of the side beating tools thereby stopped. Thus it will be seen that the starting and stopping of the side beating tools are controlled automatically by movement of the spindle or shoe 70 supporting rest with the shoe toward and from the machine. The yoke and its carried parts are adjustable from and toward the machine and are held in place by the set bolt 70. 75

Having explained the nature of this invention and fully described a machine embodying the same in the best form now known to me, and having indicated in connection with this description the way in 80 which it is contemplated the machine may be used, I claim as new and desire to secure by Letters Patent of the United States:—

1. A machine of the class described, having, in combination, a beater arranged to 85 engage the bottom of a shoe and means for reciprocating that beater, a beater arranged to engage the sides of the shoe adjacent to the portion being treated by the bottom beater, an actuator for the side 90 beater, said side beater and its actuator being normally held out of operative connection and being arranged to permit operative connection to be established by laterally directed pressure of the shoe, the parts being 95 so arranged that the operation of the side beater may be discontinued at will without interrupting the reciprocation of the bottom beater.

2. A machine of the class described, having, in combination, a bottom beater, an actuator therefor, a treadle connection for starting and variably controlling the operation of the bottom beater, a side beater, an actuator therefor, and provision for independently controlling the actuation of the side beater while the machine is running. 100

3. A machine of the class described, having, in combination, a beater arranged to operate upon the bottom of a shoe, a beater 110 arranged to operate on the side of the shoe, and actuating means for said two beaters, said machine having provision by which either beater can be started and stopped while the other beater continues in operation. 115

4. A machine of the class described, having, in combination, a reciprocating bottom beater, a reciprocating side beater, and means adapted for actuating said beaters, said machine having provision for separately controlling the operation of the bottom and side beaters including means for permitting the actuation of the side beater to be controlled by the position of the shoe. 120

5. A machine of the class described, having, in combination with suitable actuating

- means, means for treating the bottom of a shoe and a beater for treating the side of the shoe adjacent to its edge and arranged to have a component of movement toward the last bottom as the beater is advanced toward the side of the last, said side beater being constructed and arranged to be rendered operative or inoperative by changing the position of the shoe.
10. A machine of the class described, having, in combination with suitable actuating means, a shoe side beater and guiding means for causing the beater to be moved upwardly toward the plane of the shoe bottom as it is advanced, said machine being constructed and arranged to cause the actuation of the beater to be controlled by the position of the shoe.
7. A machine of the class described, having, in combination with suitable actuating means, means for treating the bottom of a shoe, a rest for the side of the shoe presenting a backwardly and downwardly inclined working face and adapted to beat the side of the shoe at times, and means for positioning the shoe vertically which means is arranged to present the shank of the shoe in a lower position than the forepart, said machine having provision for permitting the actuation of the said beater to be discontinued by the reduced pressure against it as the shoe is moved down the backwardly inclined face of the side rest.
8. A machine of the class described, having, in combination, a bottom beating tool, a side rest and a carrier for the rest, an oscillating vibrator, a link pivotally connecting the vibrator and the carrier for the rest, and a cam adapted to actuate the vibrator, said machine having provision for maintaining the rest normally in inoperative relation to its actuator and for causing an operative connection to be established by a change in the position of the shoe while the machine is running.
9. A machine of the class described, having, in combination, a shoe side rest, a carrier for the rest, a vibrator fulcrumed to a fixed support and connected to the carrier, and a cam for actuating the vibrator, said machine having provision for holding the vibrator normally away from the cam and permitting engagement thereof to be effected by varying the pressure of the work against the side rest.
10. A machine of the class described, having, in combination, side beating means comprising a plurality of contacting members arranged to turn independently about a plurality of axes perpendicular to one another, and mechanism for actuating the beating means to do its work.
11. A machine of the class described, having, in combination, means for treating the bottom of a shoe, means adapted to be rendered operative or inoperative by pressure against it for beating the side of the shoe, and means for effecting such pressure against the side beater.
12. A machine of the class described, having, in combination, means for treating the bottom of a shoe, means adapted to be rendered operative or inoperative by pressure against it for beating the side of the shoe, and means constructed and arranged to hold the shoe against the side beater to render that beater operative, and having provision for locking the shoe away from the side beater.
13. A machine of the class described, having, in combination, a side beater, a continuously running actuator, means for yieldingly holding the beater out of position to be driven by its actuator, and means arranged to be rendered operative or inoperative for holding the shoe against the side beater with a force to cause the beater to be maintained in operative relation to its actuator.
14. A machine of the class described, having, in combination, means to beat the side of a shoe, an actuator with relation to which the beater occupies normally an inoperative relation, a shoe carrier, and means to actuate the carrier and, through movement of the shoe which is mounted on said carrier, cause the beater to be moved into operative relation to its actuator.
15. A machine of the class described, having, in combination, an actuator, a normally inoperative beater for treating the side of a shoe, a shoe positioning means, and means for actuating said positioning means and, by force transmitted through the shoe, starting the beater into operation automatically as soon as the shoe is in position to receive the action of the beater.
16. A machine of the class described, having, in combination, an actuator, a normally inoperative side beater, a shoe positioning means, means for actuating the positioning means and, by force transmitted through the shoe, causing the beater to be started, and means to lock the positioning means in position to permit the beater to remain inoperative.
17. A machine of the class described, having, in combination, an actuator, a normally inoperative shoe beater, a shoe positioner, means for automatically locking the positioner with the shoe away from the beater, and means for automatically moving the shoe into operative relation to the beater and effecting the starting of the beater when the locking means is released.
18. A machine of the class described, having,

ing, in combination, devices for operating on a shoe, a shoe positioner, a slide in which the positioner is guided and which is arranged for movement by force transmitted through the positioner, and locking means for the slide arranged to operate automatically for locking the positioner when it is moved in one direction, and to be unlocked by unusual force applied in the opposite direction.

10 19. A machine of the class described, having, in combination, devices for operating on a shoe, a shoe positioner, a slide in which the positioner is guided and which is arranged for movement by force transmitted through the positioner, and a spring arranged to pull the slide and positioner inwardly, and a lock arranged to latch automatically to hold the shoe outwardly and to be unlatched by an inward pressure greater than that of

20 said spring.

20 20. A machine of the class described, having, in combination, the laterally acting beaters 40, the actuator 25 therefor, the spring 32 to hold the beaters normally away from the path of the actuator, the shoe spindle 50, the guide slide 56 therefor, the springs 58 of greater force than the spring 32 to force the beater into the path of its actuator, and the lock 62 arranged on the slide

30 to latch the spindle away from the beater.

21. A machine of the class described, having, in combination, a shoe beater, the shoe spindle 50, the yoke 55, the slide 56 carried by the yoke and through which the spindle is guided, the springs 58 to pull the spindle laterally toward the machine, and the latch 62 to secure the spindle away from the machine, said machine having provision for adjusting the yoke and slide together laterally from and toward the machine.

22. A machine of the class described, having, in combination, a shoe bottom beater, and means to actuate it to force the upper downwardly toward the last bottom and laterally inward away from the edge of the last bottom, a shoe spindle, means for rigidly upholding the spindle against the downward action of the beater, means for yieldingly holding the spindle inwardly against the laterally directed action of the beater, and means for locking the spindle away from the beater in shoe receiving position.

23. A machine of the class described, having, in combination, means for forcing the upper material downwardly toward the innersole and inwardly away from the edge of the innersole, means for blocking the shoe, means for actuating the shoe laterally toward the blocking means, and starting and stopping means controlled by such lateral movement of the shoe.

24. A machine of the class described hav-

ing, in combination, a blocking device for engaging the side of the shoe at and near its edge, an actuator for said blocking device, means positioned by movement transmitted through the shoe to establish operative connection between said actuator and the blocking device, and means for maintaining the shoe in position to cause said operative connection to be continued.

25. A machine of the class described having, in combination, a device for engaging the side of the shoe at and near its edge, mechanism to actuate said device to block the shoe, said mechanism being arranged to begin actuating said device in response to increase in pressure of the shoe against the blocking device, means for actuating the shoe toward said device and means to lock the shoe away from the blocking device.

26. A machine of the class described, having, in combination, means for treating the bottom of a shoe, actuating mechanism therefor, devices normally at rest and constantly occupying shoe guiding positions on opposite lateral sides of said means, and means to cause vibration of the said devices to be effected in response to increase in laterally directed pressure of the shoe against said devices.

27. A machine of the class described, having, in combination, a bottom beater, a side beater, operating means for reciprocating the two beaters, and means operating automatically when the work is withdrawn for discontinuing the reciprocation of the side beater without interrupting the reciprocation of the bottom beater.

28. A machine of the class described having, in combination, means for beating the side of a shoe, said beaters having each a contacting member arranged to adjust itself angularly and independently of the other contacting member about an axis extending substantially perpendicular to the plane of the shoe bottom to adapt itself to the shape of the surface being treated and mechanism for reciprocating said beaters to do their work.

29. In a machine for beating shoes, a side beater which is normally at rest, an actuator, therefor, a shoe carrier movable with the shoe toward the side beater, means acting upon the carrier for so moving the shoe, and connections to cause the beater to be automatically put into operation by such movement.

30. In a machine for beating shoes, an actuator, a side beater which is normally at rest, throughout the cycle of said actuator but can be caused to be operated thereby, a shoe carrier movable with the shoe toward the side beater, and connections to cause the beater to be automatically put into operation by such movement of the shoe.

31. In a machine for beating shoes, a side beater which is normally at rest, an actuator therefor, a shoe carrier movable with the shoe toward the side beater, means acting upon the carrier for so moving the shoe, connections to cause the beater to be automatically put into operation by such movement, and a latch to fasten the carrier against movement by said means.
- 10 32. In a machine of the class described, means for beating the side of a shoe; an actuator for the side beating means, said side beating means being normally held continuously out of operative relation with the 15 actuator throughout repeated cycles of said

actuator, and a rest for the shoe arranged for movement to carry the shoe toward the side beating means for causing operative connection between said actuator and the side beating means to be made in response to 20 such movement and thereon starting the operation of the side beating means.

In testimony whereof I have signed my name to this specification in the presence of two subscribing witnesses.

RONALD FRANCIS McFEELY.
